CLAIM

The ornamental design for a tape measure, as shown and described in the accompanying drawings.

DESCRIPTION

FIG. 1 is a front-left side perspective view of an embodiment of a tape measure, showing my design;

FIG. 2 is a front view thereof;

FIG. 3 is a back view thereof;

FIG. 4 is a right side elevation thereof;

FIG. 5 is a left side elevation thereof;

FIG. 6 is a top view thereof;

FIG. 7 is a bottom view thereof;

FIG. 8 is a front-right side perspective view thereof;

FIG. 9 is a back-right side perspective view thereof;

FIG. 10 is a back-left side perspective view thereof;

FIG. 11 is a front-left side perspective view of another embodiment of a tape measure, showing my design;

FIG. 12 is a front view thereof;

FIG. 13 is a back view thereof;

FIG. 14 is a right side elevation thereof;

FIG. 15 is a left side elevation thereof;

FIG. 16 is a top view thereof;

FIG. 17 is a bottom view thereof;

FIG. 18 is a front-right side perspective view thereof;

FIG. 19 is a back-right side perspective view thereof; and,

FIG. 20 is a back-left side perspective view thereof.
